COMBINED SHOWER-SAUNA-BATHTUB UNIT

Emmett J. Callahan, 2065 Liberty St. NE.,
Salem, Oreg. 97302

Filed Sept. 17, 1971, Ser. No. 181,652

Term of patent 14 years

Int. Cl. D23—02

U.S. Cl. D23—49

FIG. 1

FIG. 3

FIG. 2

FIG. 5

FIG. 4

FIG. 1 is a perspective view of a combined shower-sauna-bathtub unit showing my new design, a portion being broken away for purposes of illustration;

FIG. 2 is a top plan view thereof;

FIG. 3 is a side elevational view thereof;

FIG. 4 is a rear elevational view thereof; and

FIG. 5 is a cross sectional view taken on line 5—5 of FIG. 4.

The broken line representation of a showerhead and drain pipe in FIG. 1 are for purposes of illustration only.

I claim:

The ornamental design for a combined shower-sauna-bathtub unit, as shown and described.
